Found online Dec. 1, 2020 at <https://www.abt.com/product/131966/Gaggenau-24-200-Series-Glass-Front-Metallic-Single-Oven-BOP251611.html> (Year: 2020).*Primary Examiner — Robert M. Spear(74) *Attorney, Agent, or Firm* — Birch, Stewart, Kolasch & Birch, LLP(57) **CLAIM**

The ornamental design for an oven range, as shown and described.

DESCRIPTION

1. Oven range
- 1.1 : Perspective
- 1.2 : Front
- 1.3 : Back
- 1.4 : Left
- 1.5 : Right
- 1.6 : Top
- 1.7 : Bottom
- 1.8 : Perspective
- 1.9 : Front
- 1.10 : Back
- 1.11 : Left
- 1.12 : Right
- 1.13 : Top
- 1.14 : Bottom

The parts shown by means of broken lines in the reproductions are not part of the claimed design; reproductions 1.8 to 1.14 show the door in another state, the so-called see-through door becoming see-through by means of a sensor for

(Continued)

detecting approach and/or contact of person through which the cooking condition in a cooking chamber can be observed.

1 Claim, 14 Drawing Sheets
